UNITED STATES PATENT OFFICE

2,520,110

SLICING MACHINE FOOD CARRIAGE

Adrianus van Duyn, Hillegersberg, Netherlands,
assignor to U. S. Slicing Machine Company,
Inc., La Porte, Ind., a corporation of Indiana

Application August 4, 1947, Serial No. 766,028
In Great Britain October 14, 1946

4 Claims. (Cl. 146—102)

1

This invention relates in general to a slicing machine of the so-called "gravity feed" class, as disclosed in application Serial No. 766,025, filed August 4, 1947, wherein the slicing machine is crossed by an inclined carrier down which the substance to be sliced moves step by step, under the influence of gravity, and under the control of a slice thickness gauge, to a rotary cutting knife.

More specifically, the invention relates to a carriage construction for slicing machines of the type disclosed in the copending application filed August 4, 1947, Serial No. 766,026, wherein there is disclosed a slicing machine having a reciprocating carriage that comprises two components which are detachably interconnected to form a rigid structural unit, the upper component being the substance carrier and the lower component being a support which is reciprocable along one or more guides on the machine frame, being constrained by said guide or guides to longitudinal movement; that is to say, the support component is constrained against movement relative to the slicing plane.

The present invention is an improvement of the structure disclosed in the aforesaid copending application, Serial Number 766,026, and as disclosed specifically in the other aforementioned application, Serial No. 766,025, filed August 4, 1947.

According to the present invention, in a slicing machine of the class stated, the gravity feed carrier is connected to a longitudinally guided support by male and female joint members and which is disconnected by the act of lifting the carrier.

Further, according to the present invention, in a slicing machine of the class stated, the gravity feed carrier is connected to a longitudinally guided support by a main pin-and-socket joint with which is associated an auxiliary joint adapted to prevent rotational movement of the carrier in relation to the support about the axis of the main joint, the arrangement being such that the carrier can be disconnected by the act of lifting it from the support.

In an example, the gravity feed carrier has two dependent pins, the main one of them being a long pin; and the longitudinally guided support has a socket into which the main pin fits and a fork-like member with a slot into which the auxiliary pin fits. The carrier comprises an inclined trough which fits upon a holder formed with two bosses, both facing vertically downwards. The two dependent pins are secured to these bosses, and both pins are vertical. The

2

boss of the main pin is arranged in a position where it can best take the weight of the carrier when loaded. The support is a bracket incorporated in a longitudinally guided reciprocable carriage; and the bracket is formed with a pillar and is provided with a handle by means of which the operator can push and pull the carriage. The pillar is a socket, having a long vertical hole. The top portion of this hole is formed as an upper bearing for the main pin, and the lower end of the hole is formed as a foot-step bearing for the foot of the main pin. A holding-down screw at the bottom of the hole has a head upon which the slightly tapered foot of the main pin rests. The pillar has a lateral arm to which is secured a horizontal two-pronged fork, a rounded slot being formed between the prongs to engage the auxiliary pin. The boss of this pin is dished out so that the fork is enclosed by the boss.

The arrangement is such that the main joint takes the weight of the carrier and the substance thereon, whereas the main and auxiliary joints cooperate to take the forces due to the reciprocating motion of the carriage and due to the slicing action of the knife, the auxiliary joint preventing rotational motion of the carrier about the axis of the main pin.

The carrier is disconnected from the rest of the carriage simply by lifting it vertically from the support, there being no need for the use of tools.

The accompanying drawing illustrates a selected embodiment of a food trough or carriage which is adapted to be reciprocated along a rectilinear path and has a trough portion which is disconectable from a standard, and the views therein are as follows:

Fig. 1 is a detail elevational view of a food trough or carriage which is adapted to be used in connection with a slicing machine, particularly of the gravity feed type; and

Fig. 3 is a detail transverse sectional view on the line 2—2 of Fig. 1.

The particular construction shown herein for the purpose of illustrating the invention comprises a base 1 which houses a longitudinal slide bar 2 to guide a carriage member 3 which extends beneath or through a side wall of the base. A guide rod 4 is also positioned below the base, there being a roller 5 on the carriage member 3 so that the carriage member will be guided and supported by the slide bar 2 and the guide rod 4. A pillar or standard 6 is connected to the carriage member 3 and extends upwardly and vertically therefrom. This pillar or standard 6 may

be made an integral part of the carriage member 3 but is preferably made as a separate unit and is detachably connected to the said carriage member. A knob or handle operating member 7 is connected rigidly to the standard 6 to shift the carriage member and standard longitudinally in a rectilinear path. The standard or pillar 6 has a vertical opening 8 formed therein to receive a pin 9 on a V-shaped trough 10. The pin 9 is shown connected to a boss 11 on the V-shaped trough, but the pin 9 may be fixed in the vertical opening 8 in the standard and received in an aligned cooperating vertical opening 12 in the boss 11. It is preferable, however, that the pin 9 be secured to the boss and extend downwardly in the vertical opening 8, as clearly shown in the drawing. The bottom of the pin 9 may be made non-circular at its bottom end to fit in a cooperating non-circular opening at the bottom of the vertical opening 8. The trough 10 is adapted to be reciprocated longitudinally along a rectilinear path so that substance on the trough 10 may be cut by a circular rotating slicing knife 13.

The trough 10 has a second boss 14 rigidly secured thereto and extending downwardly parallel with the boss 11 but spaced therefrom and in a different horizontal plane. The standard 6 has an extension 15 extending inwardly and adjacent the second boss 14. This extension 15 has a member 16 rigidly secured thereto in any suitable manner such as by fastening screws 17. The end of the member 16 is provided with a bifurcated end 18 providing a slot 19. This slot 19 is adapted to receive a pin 20 fixed in a bore in the second boss 14, the bottom of the extension 15 and the bottom of the second boss 14 being recessed, as clearly shown in Fig. 2, to receive the member 16 so as to overcome any projecting parts and to make the bottom of the member 16 flush or substantially flush with the bottom surfaces of the second boss 14 and the extension 15.

The construction is such that the V-shaped trough 10 may be removed by merely raising the food trough upwardly so that it will become detached from the supporting pin 9 and the second supporting pin 20 and its cooperating member 16. The member 16 and its disconnectable connection with the pin 20 prevents any pivotal movement of the food trough 10 about the vertical pin 9. The pin 9 absorbs the majority of the weight and strain as the majority of the weight will be applied to the boss 11 and the upper part of the standard or pillar 6. The pin 20 and the bifurcated member 16 will also assume some of the weight, but the main purpose of these latter elements is to prevent shiftable movement of the food trough 10 with respect to the standard 6.

The carriage member or food trough is adapted to be slid back to and fro in a rectilinear path by merely grasping the knob 7 so as to bring substance on the V-shaped trough 10 past the cutting plane of the knife 13. The handle is grasped, and the carriage member 3 and its cooperating V-shaped trough is reciprocated by pushing or pulling the handle or knob 7.

The invention provides a relatively simple device which permits the food trough to be removed from its cooperating support or standard by merely lifting it upwardly without the use of tools.

Changes may be made in the form, construction and arrangement of the parts without departing from the spirit of the invention or sacri-

ficing any of its advantages, and the right is hereby reserved to make all such changes as fairly fall within the scope of the following claims.

5 The invention is hereby claimed as follows:

1. A slicing machine comprising a base, a slide member concealed within the base, a standard on the slide member, an article support mounted on said standard, telescoping detachable supporting means for removably mounting said article support on said standard, an arm extending outwardly at one side of said standard and having an opening therein, and a member on said article support having engagement with the opening in said arm, whereby to prevent shifting between said article support and standard.

2. A slicing machine comprising a base, a slide member concealed within the base, a standard on the slide member, an article support mounted on said standard, telescoping detachable supporting means for removably mounting said article support on said standard, an arm extending outwardly at one side of said standard and having an open ended slot therein extending inwardly from the outer end thereof, and a member on said article support adapted to be received by the slot in said arm, whereby to prevent shifting between said article support and standard.

3. A slicing machine comprising a base, a slide member concealed within the base, a standard on the slide member, an article support mounted on said standard, telescoping detachable supporting means for removably mounting said article support on said standard, a horizontally projecting portion on said standard having a recess in one side thereof, an arm extending outwardly at one side of said standard having an opening in one end thereof and having its other end received within said recess, whereby the outer surfaces of said arm and projecting portion are flush, and a member on said article support adapted to be received by the opening in said arm, thereby to prevent shifting between said article support and said standard.

4. A slicing machine comprising a base, a shiftable carriage slidably mounted within the base, a standard on the carriage, an inclined article support carried by the standard, means telescopingly and disconnectably engaging the article support and the standard, projecting means on said standard extending laterally therefrom, and a member extending downwardly from said article support and having disconnectable engagement with said projecting means, said article support being freely removable from said standard by lifting the support upwardly.
